Patented Oct. 24, 1967

209,001

COMBINATION TOOL

Joseph N. Amigone, 3404 Main St.,
Buffalo, N.Y. 14214

Filed Dec. 8, 1965, Ser. No. 109

Term of patent 14 years

(Cl. D44—29)

FIG. 2.

FIG. 1.

FIG. 3.

FIG. 1 is a plan view of a combination tool, showing my new design therefor;

FIG. 2 is a side elevational view thereof; and

FIG. 3 is a view like that of FIG. 2, but with the near handle and jaw portions broken away about as indicated by line III—III of FIG. 1.

The characterizing feature of my design resides in the particularly configured cork-screw receiving recess in one face and edge of one arm in combination with the separation of the arms at the pivot of the corkscrew member and the particular configuration of the opposite arm member above the said pivot.

This application is a continuation-in-part of my earlier filed application Ser. No. D 82,736 of Nov. 23, 1964, now abandoned.

I claim:

The ornamental design for a combination tool, substantially as shown and described.
